UNITED STATES PATENT OFFICE.

ANDERS GUSTAVUS ANDERSON, OF WORCESTER, MASSACHUSETTS, ASSIGNOR
TO EDMUND CONVERSE, OF SAME PLACE.

METHOD OF MAKING SHEET-METAL CUPS.

SPECIFICATION forming part of Letters Patent No. 671,427, dated April 9, 1901.

Application filed September 22, 1897. Serial No. 662,542. (No model.)

To all whom it may concern:

Be it known that I, ANDERS GUSTAVUS ANDERSON, a citizen of the United States, residing at Worcester, in the county of Worcester 5 and State of Massachusetts, have invented a new and useful Improvement in Methods of Making Sheet-Metal Cups, of which the following is a specification, reference being made to the accompanying drawings, forming a part 10 of the same.

My present invention relates to a sheet-metal cup having a square corner between its bottom and side wall, said cup being especially designed for ball-bearings such as are 15 used in bicycles or other vehicles, said cup being formed from sheet metal which is drawn or stamped into shape by suitable dies without heating the metal; and it consists of a flanged cup in which the side and bottom of 20 the cup are upset to form a right-angled corner and in which the side of the cup and the flange are made to form a right angle, and I accomplish this result by means of the process 25 hereinafter described.

Referring to the drawings, Figure 1 represents a circular sheet-metal blank. Fig. 2 represents a sectional view of a sheet-metal cup drawn from a circular blank in a die-press in the usual and well-known manner. 30 Fig. 3 represents a sectional view of a sheet-metal cup with a portion of the metal removed from the inside of the cup, forming a shoulder near the edge of the cup and reducing the thickness of the side wall between the 35 shoulder and the edge of the cup. Fig. 4 represents a sectional view of the sheet-metal cup with its edge expanded outwardly and obliquely to the sides of the cup. Fig. 5 represents portions of a pair of dies by which 40 certain steps in my improved process are carried on, a portion of the lower die being shown in vertical central sectional view with a sectional view of the cup in position to be acted upon by the dies. Fig. 6 represents the same 45 dies shown in Fig. 5, but with a thicker supporting-block for the cup and with a sectional view of the cup nearer completion. Fig. 7 is 50 a central sectional view of a ball-cup made by the process heretofore practiced, and Fig. 8 55 is a central sectional view of one of my improved ball-cups.

Similar letters refer to similar parts in the different figures.

In the manufacture of my improved ball-cup I first cut from a sheet of metal a circular blank A, which I form by suitable dies into a cup B in the usual and well-known manner, the operation of drawing the blank into the cup-shaped form shown in Fig. 2 necessarily making the corner B' between the 60 bottom and side of the cup rounded, as the strain required to draw the corner at right angles would produce checks or seams in the metal. The cup B is then placed in a revolving chuck, and a portion of the metal on the 65 inside of the cup and near the edge is removed by a suitable cutting-tool, thereby reducing the thickness of the side walls, as at B², and forming a slight interior shoulder B³ at a short distance from the edge of the cup. 70 The cup, as represented in Fig. 3, is then placed in a die-press, and the edge of the cup is expanded outwardly, forming a flange C, standing at an oblique angle with the side of the cup. The cup B, with the expanded flange 75 C, is then placed in the die D, with the bottom of the cup resting upon a block E, which supports the cup, with the oblique flange C above the upper horizontal face of the die D and with the sides of the cup projecting above 80 the upper face of the die D, as at C', about one thirty-second of an inch. The cup is then subjected to the action of a reciprocating die F, having a horizontal face F', which strikes upon the oblique flange C to carry it down 85 upon the upper face of the die D. The die F has also a circular concentric projection F², which enters within the cup B. When the oblique flange C has been driven down upon the upper horizontal face of the die D, the 90 block E is replaced by a thicker block, which raises the flange about one thirty-second of an inch above the horizontal face of the die D, and pressure is again applied by the die F to force the flange against the horizontal 95 face of the die D. This operation is repeated, usually three or four times, substituting at each operation a supporting-block about one thirty-second of an inch thicker than the preceding block. Each blow of the upper die F 100 forces the sides B⁴ of the cup downward and gradually upsets the metal in the rounded

corner B' until it fills the space D' around the cup, forming a square corner B⁵ between the sides and bottom of the cup, and the flange H is turned at right angles to the side wall, forming a right-angled corner H' between the flange and the sides of the cup and in the plane of the shoulder B³. In Fig. 6 I have shown the cup B as completed by the successive operations of the dies D and F, with the cup held in the die D and supported upon a block E', which is thicker than the block E. The lower die D and the cup-supporting blocks E E' are supported in the usual manner upon a table G. By the method now usually employed it is found necessary to shape the ball-cup substantially as shown at I, Fig. 7, with an outward flange J and a rounded corner J' at the edge of the cup and also with a rounded corner J² at the bottom of the cup. The ball-cup made by my improved process is completed by punching a hole K in the bottom of the cup for the spindle or shaft to pass through and by turning off the flange H, concentric with the axis of the cup, the completed cup being represented in Fig. 8, having square or right-angled corners B⁵ and H'.

The method of cutting the circular blank A, shaping the cup B, reducing the thickness of the side wall to form the shoulder B³, and expanding the edge of the cup outwardly and obliquely to the side of the cup will be well understood by those conversant with the art of working sheet metal, and therefore I have not deemed it necessary to illustrate or describe the same.

Although the operation of forming a cup-shaped blank, such as that shown in Fig. 2, and forming an outward flange thereon by the action of dies substantially like those shown in Figs. 5 and 6 is well known, the method embodying my present invention is essentially different from any heretofore produced and forms a ball-cup different from and superior to those formed by any of the practiced methods known to me. The novelty of my improved process consists in forming an interior shoulder in a cup-shaped blank, such as that shown in Fig. 3, by removing a portion of the metal from the inside and edge of the cup-shaped blank, so that when the outer flange has been turned over, as shown in Fig. 6, and the blank raised within the die D by the insertion of a thicker supporting-block beneath it a square inner corner at the edge of the blank instead of a rounded corner will be presented to the action of the reciprocating die F, so that when the flange H is raised above the face of the die D by the insertion of a thicker block beneath the cup-shaped blank and pressure is applied by the die F the side B⁴ of the cup-shaped blank will be pushed bodily down, thereby upsetting the metal in the rounded corner B' of the blank until it fills the space D' and forms a square corner between the sides and bottom of the cup. When the inner corner of the cup-shaped blank is rounded,

as would be the case if the flange were turned without cutting away the metal to form the shoulder B³, the application of pressure by the die F when the cup-shaped blank was raised in the die D would tend to crowd the side of the cup-shaped blank over and increase the width of the outward flange without upsetting the metal at the rounded corner B⁵ of the cup-shaped blank. The method hitherto practiced for forming a square corner at the bottom of the cup-shaped blank is to expand the metal by a pressure applied to the inside of the cup-shaped blank by which the metal was expanded to fill the corner D' of the die. To accomplish this result it is usually necessary to heat the blank, and the square corner is only formed by the expansion or stretching of the metal, whereas by my process the metal is upset instead of stretched and can be readily worked cold.

What I claim as my invention, and desire to secure by Letters Patent, is—

1. The process of making a sheet-metal cup having a square shoulder between its bottom and side wall, by forming a cup-shaped blank having a rounded corner between its bottom and side wall, forming an interior shoulder, turning an exterior flange on the plane of said interior shoulder and upsetting the side wall by pressure applied to the edge of the side wall in a line parallel with the axis of the cup-shaped blank while the bottom and side wall are supported against outward expansion, substantially as described.

2. The process of making a sheet-metal cup having a square shoulder between its bottom and side wall, by forming a cup-shaped blank having a rounded corner between its bottom and side wall, forming an interior shoulder, turning an exterior flange on the plane of said interior shoulder, successively upsetting the side wall by pressure applied to its upper edge while the bottom and side wall are supported against outward expansion and successively raising said cup-shaped blank by increasing the thickness of its bottom-support during the operation of upsetting the side wall, substantially as described.

3. The method of making a sheet-metal cup having a square shoulder between its bottom and side wall, by drawing a cup-shaped blank from sheet metal having a round corner between its bottom and side wall, forming an interior shoulder, turning an exterior flange, upsetting the metal between the bottom edge of the side wall by means of a die F while the blank is held in a die D, having a bottom E, with its exterior flange raised above the upper surface of the die D, and supporting the interior shoulder by a concentric projection on the die F, substantially as described.

4. The within-described method of making a flanged sheet-metal cup for ball-bearings, consisting in reducing the thickness of the side wall of a cup-shaped blank by removing a portion of the metal therefrom and forming an interior shoulder B³ near its edge, turning

the reduced section of the blank to form an outward flange H by means of suitably-shaped dies, supporting the flanged cup-shaped blank in a die D corresponding with 5. the size and shape of the ball-cup with the flange H slightly raised above the face of the die D, and applying pressure to the surface formed by the outward flange H and the shoulder B³ by means of a die F in a line parallel with the axis of the cup while the inte-

rior of the blank is supported by the concentric projection F², whereby the side of said cup-shaped blank is pushed bodily downward, causing the metal to be upset and form a square corner, substantially as described. 15

Dated this 18th day of September, 1897.
ANDERS GUSTAVUS ANDERSON.
